UNITED STATES PATENT OFFICE.

WILLARD McC. REID, OF EVANSTON, ILLINOIS, ASSIGNOR TO REID-GEISLER MANUFACTURING CO., OF CHICAGO, ILLINOIS, A CORPORATION OF ILLINOIS.

SANITARY VENTILATED DISH-MOP.

1,298,788.

Specification of Letters Patent.

Patented Apr. 1, 1919.

Application filed June 8, 1918. Serial No. 238,810.

To all whom it may concern:

Be it known that I, WILLARD McC. REID, a citizen of the United States, residing at Evanston, in the county of Cook and State 5 of Illinois, have invented a certain new and useful Improvement in Sanitary Ventilated Dish-Mops, of which the following is a specification.

This invention relates to mops used in 10 washing dishes, the same as ordinarily sold in the trade, comprising a wooden handle with a swab of cotton threads tied thereto. As ordinarily constructed, the device is apt to become unsanitary in use due to the fact 15 that portions of mop material proper which come in contact with the wooden handle have little chance to dry out and consequently become sour, with consequent unpleasant odor and other unsanitary results. 20 The object of this invention is to so construct the mop that air can pass through the center of the swab or mop body proper, to assist in drying it out and rendering it sanitary. The invention consists in means for 25 carrying out the foregoing objects which can be easily and cheaply made; which is satisfactory in operation and not readily liable to get out of order. More in detail, the invention consists in the features and 30 details of construction which will be hereafter more fully set forth in the specification and claims.

Referring to the drawings, in which similar numerals indicate the same parts 35 throughout the several views—

Figure 1 is a side view of a mop having the device of this invention applied thereto.

Fig. 2 is a central sectional view through 40 the attaching portion of the mop handle, illustrating the device in detail.

In constructing the device of this invention, an ordinary cylindrical handle 10 is provided to which the mop member 12 is to be attached. Instead of attaching the 45 mop 12 directly to the handle, as has been the usual practice heretofore, a metallic tubular member 14 is provided, preferably having formed upon it two circular ridges 16 and 18, constructed approximately as 50 shown. Into one end of this tubular member 14 is fitted the more or less contracted end portion 20 of the handle 10, the same being secured in place by any suitable means, such

for instance as pin or rivet 22. The remaining portion of the tubular member 14 and 55 particularly that portion between the ridges 16 and 18, is provided with a large number of perforations 24 of sufficient size so that air can readily pass through them. About the tubular member 14 and over these perforations 24 is placed a mop member 12, secured in place by any suitable means, as for instance by a band 26. This band may be placed at any point, but is preferably located as shown intermediate of the length 60 of the perforated portion of the tubular member 14 so that air may pass through and around the mop material and through the holes 24 to the central interior passage-way 28 of the tubular member. The upper 65 edges 30 of the mop member 12, being thus free to bend away from the upper portion of the tubular member 14, thus making a clear passage through the upper holes 24 for this ventilating purpose. 70

In the operation of the device, the mop is used in the ordinary manner, whereupon it is either hung up by any suitable means not shown, in the vertical position shown in the drawing, with the result that the tubular 80 member 14 holds the central portions 32 of the mop in separated position part for part, as shown in Fig. 2 so that air can pass up through the center of the mop, thence through the holes 24, through and around 85 the mop material on the exterior of the handle, in the obvious manner and as heretofore described, or the mop can be inverted so that the mop material falls away from the end of the tube 14, leaving entrance to 90 passage 28 wide open with obvious results.

Having thus described my invention, what I claim as new and desire to secure by Letters Patent, is:—

1. In a device of the class described, in combination with a body of mop material, a perforated tubular member inserted inside the body of said mop material in such a way that air can pass through said tubular member and the perforations therein into 100 the mop material for the purpose of obtaining ventilation of the complete mop and a handle device connected to the tubular member, for the purposes set forth. 95

2. In a device of the class described, a 105 tubular member, a handle entering one end

of the tubular member, for a portion of the length thereof, means securing the handle to the tubular member, a body of mop material attached to the tubular member beyond the end of the handle, there being perforations in the tubular member surrounded by the mop, for the purposes set forth.

In witness whereof, I have hereunto subscribed my name in the presence of two witnesses.

WILLARD McC. REID.

Witnesses:

DWIGHT B. CHEEVER,
M. S. ROSENZWEIG.
